CLAIM

The ornamental design for a tent with two ridge poles, as shown and described.

DESCRIPTION

FIG. 1 is a front perspective of a tent showing our new design including a fly;

FIG. 2 is a front elevational view thereof;

FIG. 3 is a right side elevational view thereof, the left side elevational view being a mirror image thereof;

FIG. 4 is a rear elevational view thereof;

FIG. 5 is a front perspective with the fly removed;

FIG. 6 is a front elevational view thereof with the fly removed;

FIG. 7 is a right side elevational view with the fly removed, the left side elevational view being a mirror image thereof;

FIG. 8 is a rear elevational view with the fly removed; and,

FIG. 9 is a top plan view with the fly removed.

FIGS. 5-9 are show the fly detached for clarity of illustration.
